UNITED STATES PATENT OFFICE.

FREDERICK W. WAKEFIELD, OF VERMILION, OHIO, ASSIGNOR TO THE F. W. WAKEFIELD BRASS COMPANY, OF VERMILION, OHIO, A CORPORATION OF OHIO.

LIGHTING-FIXTURE.

1,086,874.

Specification of Letters Patent.

Patented Feb. 10, 1914.

Application filed September 23, 1908. Serial No. 519,187.

To all whom it may concern:

Be it known that I, FREDERICK W. WAKEFIELD, a citizen of the United States, and a resident of Vermilion, county of Erie, and 5 State of Ohio, have invented a new and useful Improvement in Lighting-Fixtures, of which the following is a specification, the principle of the invention being herein explained and the best mode in which I have 10 contemplated applying that principle, so as to distinguish it from other inventions.

My invention relates to lighting fixtures with which electricity is used as the lighting medium. It will, of course, be understood that in the use of electric fixtures it is necessary to provide some method of insulating the wires against any possibility of grounding, with the consequent injury to the fixture or the building in which it is installed. In electric fixtures in which a chain support is used, it is usual to intertwine the wires with the links of which the chain is composed, and my invention relates in particular to an improved method of insulating 25 such a chain supported fixture.

To the accomplishment of this and related ends, said invention, then, consists of the means hereinafter fully described and particularly pointed out in the claim.

30 The annexed drawing and the following description set forth in detail certain mechanism embodying the invention, such disclosed means constituting, however, but one of the various mechanical forms in which 35 the principle of the invention may be used.

In said annexed drawing: Figure 1 is an elevation of a fixture embodying my invention; Fig. 2 is a side elevation of one of the links of which the chain is composed; 40 Fig. 3 is a front elevation of a link; Fig. 4 is a side elevation of the top link of the series; Fig. 5 is a cross section of such top link attached to the pipe inclosing the feed wires; Fig. 6 illustrates a modified supporting member; and Fig. 7 is a section through 45 two connecting links.

The fixture in general comprises a pipe A depending through the ceiling and inclosing the feed wires, an ornamental canopy a 50 surrounding the pipe adjacent to the ceiling. Depending from the pipe A is the chain B which supports the fixture body C with the arms attached thereto. This chain B is composed of a series of similar links b; 55 these links may be of any suitable orna-

mental form, but the flattened links as shown are adapted to yield great rigidity to the chain and yet to preserve an ornamental appearance. The top link of the series is open at one end and has its two lateral extensions attached to the rod inclosing the feed wires. Fig. 6 illustrates a form which may be used instead of the top link of the series as described. This form comprises a hook E adapted to be screwed onto 60 the pipe and to receive and support one of the pipe and to receive and support one of the series of similar links.

The insulating material D is disposed upon the inner surfaces of these links and is attached thereto in any suitable manner. 70 The insulation, instead of being merely the width of the link, is made somewhat wider and extends beyond the edges of the surfaces of the links, as is clearly seen by an examination of Fig. 2. This extension of 75 the insulation beyond the edges of the surfaces to which it is attached renders contact of the metallic connecting links impossible.

From this brief description, it will be evident that my improved disposition of the 80 insulating material in such a fixture renders grounding of the wires impossible. By making the insulation a component part of the chain supporting the fixture proper an increased protection is obtained, and at the 85 same time there is no sacrifice of the ornamental appearance of the fixture. In the figures, the insulating material is shown as being disposed upon the surfaces of all of the links in the chain. It is preferable, however, that the insulation be installed merely 90 between the two top links, or between the top link and the supporting hook; this limited insulation will be found sufficient and wholly effective.

95 It is readily apparent that the insulation disposed according to my invention, especially if installed merely upon the upper links, will be very inconspicuous, and will detract in no way from the appearance of the 100 chain fixture. At the same time, the great reduction in expense is of much practical importance, for it is obvious that this method of installing the insulation will cost much less than when the insulation is inserted at one of the threaded joints, as is 105 done in the prevailing method of insulating fixtures of this type.

Other modes of applying the principle 110 of my invention may be employed instead

of the one explained, change being made as regards the mechanism herein described, provided the means stated by the following claim or the equivalent of such stated means 5 be employed.

I therefore particularly point out and distinctly claim as my invention:—

As a new article of manufacture, a pendant support for an electric light fixture, 10 including a plurality of interengaging flattened links, and corresponding flat sheets of insulating material bent to conform with the inner faces of said links, such sheets being slightly wider than the inner faces of 15 said links, and being suitably attached thereto, so as to extend beyond the edges of

the same, thereby preventing contact between said links when moved slightly relatively to each other while not preventing such movement such sheets being maintained 20 in place if loosened in any one link by the adjacent link or links engaging such first link, the form of said links being designed to prevent any bending strain being put upon said links which would tend to loosen 25 said sheets of insulating material therefrom.

Signed by me this 11th day of Sept. 1909.

FREDERICK W. WAKEFIELD.
